UNITED STATES PATENT OFFICE.

EDMUND A. DEBUCHY, OF WEST HOBOKEN, NEW JERSEY.

LOADING DEVICE FOR MAGAZINE-GUNS.

1,178,785.

Specification of Letters Patent. Patented Apr. 11, 1916.

Application filed May 26, 1915. Serial No. 30,527.

To all whom it may concern:

Be it known that I, EDMUND ALFRED DEBUCHY, a citizen of the United States, and resident of the town of West Hoboken, county of Hudson, State of New Jersey, have invented certain new and useful Improvements in Loading Devices for Magazine-Guns, of which the following is a specification.

10 The device the subject of this invention, is intended as a means for arranging cartridges in position to be inserted into the magazine of a gun, and although the device may be used with almost any type of magazine gun, I have shown it in connection with what is commonly termed a tube magazine or pump gun.

20 The device receives cartridges from the container in which they are packed and in any general condition. The cartridges are merely dumped into my device and when therein will, by the operation of the mechanism be arranged in regular order and pointing in a general direction, the direction in 25 which they are to be received in the magazine of the gun.

30 The device here shown is intended to operate with cartridges having a rim, and if built in proper size and proportion will efficiently handle cartridges used in rifles, shot guns, or revolvers for hand use or even any of the larger guns used for field service.

35 The construction and operation of my device will be fully described in the specification which follows.

40 The following is what I consider the best means of carrying out my invention and the accompanying drawings form a part of this specification, in which:

45 Figure 1 shows a small rifle or gun in position for loading, with my device in position. Fig. 2 is a side elevation of my device. This figure is on a large scale and is partly broken away to show the arrangement of the cartridges ready for delivery. Fig. 3 is a vertical section. Fig. 4 an enlarged perspective view of one of the shutters. Fig. 5 is a perspective and partial sectional view of a device having a plurality 50 of compartments. Fig. 6 is a sectional view of Fig. 5, showing shutters of modified construction.

55 Similar reference numerals indicate like parts in all of the figures where they appear.

At 1 and in Fig. 1, I have indicated a small gun or rifle of the tubular magazine

variety, and of a type which may be called a hand gun for the reason that it is intended to be held in the hand and otherwise unsupported when operated. This gun requires 60 no changes in construction or modifications for use with my device and I will therefore not describe it in detail, considering it sufficient to indicate the body of the gun at 1 and the magazine tube at 2, which tube is 65 provided with a loading aperture or opening as indicated at 3.

70 My device consists of a hopper or body portion indicated at 4 into which a quantity of loaded cartridges may be dumped. To prevent the cartridges falling from the magazine portion I may arrange a cover 5 closing the upper, otherwise open end of the hopper. Formed integral with or secured to the hopper is the delivery chute indicated 75 at 6, and arranged within this chute and forming the side walls thereof is a pair of ways indicated at 7 and 8. The space between these ways is sufficient to receive the body portion of a cartridge and the bullet 80 arranged therein, but not sufficient to receive the rim of the cartridge.

85 Cartridges operable with my device are indicated at 9, 10, and 11, and it will be observed that the cartridges may be of any length, but to use a cartridge of larger diameter it will be necessary to provide a device having a greater distance between the ways 7 and 8.

90 Arranged between the hopper 4 and the delivery chute 6 is a shutter 12 operable by means of a button 13. The shutter which may become a part of the side wall of the chute, or hopper, need not entirely close the lower end of the hopper nor the upper end 95 of the chute, it being found sufficient, to close these passages only to an extent to prevent the passage of cartridges therethrough at such time as it is desirable to retain them in either of these chambers, and in 100 addition I find it quite desirable to keep the width of the shutter as small as possible so that the radius of its operations shall not interfere with the cartridges contained in either chamber.

105 In operating my device the cover 5 is open and a number of cartridges are dumped or placed in the hopper 4, the cover is then closed. Now, when the shutter 12 is turned outward until it lies on a plane parallel to 110 the side of the hopper, a number of the cartridges will fall between the ways 7 and 8 and

vill there be suspended by their rim resting on the top edges of the ways. The shutter may now be closed or it may be allowed to automatically close itself by the action of the spring 14. The cartridges will then be found to be in position to be inserted in the magazine of the rifle. Next the rifle is turned bottom upward and the magazine opened, and when my device is placed adjacent to the magazine with the open end 15 in register with the opening 3 in the magazine the cartridges will roll from the delivery chute and from between the ways hereof into the magazine of a rifle.

It will appear as obvious that the delivery chute may be large enough to contain a number of cartridges sufficient to fill the magazine of the gun, but this is not entirely necessary as the size of my device and the number of cartridges which it will contain may be changed at will.

Fig. 5 indicates that my device may consist of a plurality of hoppers 4^a each provided with its own delivery chute. This construction has its advantages in that a greater supply of cartridges may be retained always ready for use. A greater advantage to this construction resides in the fact that cartridges of different lengths may be retained in the hoppers ready for immediate use under changing conditions, or if the device is used with a shot gun, cartridges having different charges may be loaded into the separate compartments of the hopper.

It will be observed that the body of my device is slightly curved, the intention being to so shape it that it may fit more snugly in a coat pocket and conform to the body of the wearer of the coat, thus it will occupy less space and not interfere with the movement of the operator. There is a more important reason for the particular shape that I have given my device for when the chute has been filled from the hopper the mere turning of the device into a horizontal position will cause the cartridges in the hopper to fall away from the shutter clearing its path of movement and allowing it to be readily closed.

At 17 I have indicated a plug formed integral with the shutter 12 or secured thereto, and at 18, and in the side-wall of the hopper I have indicated certain perforations. The spring 14 forces the shutter longitudinally in the direction of the knob and when the shutter is to be turned the knob is pressed inward sufficient to disengage the plug 17 from the perforation 18; the knob and shutter may then be turned, and at the full extent of the motion the plug will engage in the perforation 18 or under the edge of the casing.

I have indicated a stop 16 as secured to or formed integral with the shutters, and when the shutter is turned in a flat or hori-

zontal position the stop will project into the path of the cartridges arranged on the ways 7 and 8 and will prevent the discharge therefrom at an inopportune time, it being only necessary to turn the shutter 76 to remove the stop out of the line of the cartridges. This stop 16, may however, be dispensed with if care is taken that cartridges are not left in the chute after the magazine has been charged.

Other modifications may be made within the scope of the appended claims without departing from the principle or sacrificing the advantages of this invention.

Having carefully and fully described my invention to the best of my ability, what I claim and desire to secure by Letters Patent is,

1. Means for loading the magazines of guns, which consists of a hopper, a chute provided with a plurality of ways arranged adjacent to said hopper, and a revoluble shutter between said hopper and said ways, and means for operating said shutter, as and for the purpose set forth.

2. A device of the character described, comprising a hopper having a plurality of sections, a plurality of delivery means from said sections, chutes arranged adjacent to said sections and means for controlling the delivery from said chutes as and for the purpose set forth.

3. A device of the character described, having in combination with the magazine of a gun a chamber exterior to said magazine and comprising a hopper, ways adjacent thereto, a shutter adjacent to said ways, and means for temporarily retaining said shutter in position to prevent the delivery from said hopper to said ways as and for the purpose set forth.

4. The device of the character described, comprising a hopper, a chute, arranged at an angle to said hopper, and provided with a plurality of ways adjacent to said hopper, and means for controlling the delivery from said hopper into said ways as and for the purpose set forth.

5. The device of the character described, consisting of a hopper, a chute adjacent to said hopper, a shutter between said hopper and said chute, and a stop to prevent the delivery from said chute when said shutter is open.

6. A device of the character described comprising a hopper, a chute, arranged at an angle thereto, and provided with a plurality of ways, a revoluble shutter between said hopper and said ways, and a stop attached to and operable with said shutter to prevent the delivery from said ways when the said shutter is open.

7. A device of the character described consisting of a hopper, a shutter for closing the inner end of said hopper, and means

for closing the outer end of said hopper in combination with a delivery chute formed integral with and at an angle to said hopper as herein specified.

- 5 8. A device of the character described comprising a hopper, ways adjacent thereto, a shutter adjacent to said ways means for temporarily retaining said shutter in position, to prevent the delivery from said hopper to said ways and means for moving said shutter longitudinally to engage the said retaining means as herein specified.
- 10 9. A device of the character described

comprising a hopper, ways adjacent thereto, a shutter adjacent to said ways and resilient means for urging said shutter into a temporarily retained position to prevent the delivery from said hopper to said ways as and for the purpose set forth.

Signed at city of New York, county and 20 State of New York, this 8th day of May, 1915, in the presence of these two witnesses.

EDMUND A. DEBUCHY.
